VEHICLE HEAD LAMP

Wilhelm Honing, Eindhoven, Netherlands, assignor to General Electric Company, a corporation of New York

Application November 20, 1934, Serial No. 753,876
In Germany December 22, 1933

4 Claims. (Cl. 176—26)

My invention relates to vehicle headlamps and more particularly to an incandescent electric lamp for use therein having a novel filament arrangement for producing a desired light distribution.

One of the objects of my invention is to provide a filament arrangement in a headlamp whereby a driving beam is produced having a "hot spot" of light of high intensity and of uniform shape and comparatively large depth, while the beam for use when approaching an oncoming vehicle is of comparatively wide lateral spread.

According to my invention the above object is attained by employing a pair of filaments in the lamp arranged in substantially the shape of a T with the filament constituting the vertical leg of the T arranged in a vertical plane which preferably passes through the focal point of the reflector. The said vertical filament is used to produce the "driving" beam and the horizontal filament is used to produce the "meeting" beam.

Further features and advantages of my invention will appear from the following detailed description of species thereof.

In the drawing, Fig. 1 is a perspective view of an incandescent lamp with a filament arrangement according to my invention; Fig. 2 is a front view thereof; Fig. 3 is a diagrammatic showing of a section of a driving beam produced by the lamp; and Fig. 4 is a similar showing of a meeting beam.

Referring to Figs. 1 and 2, the lamp comprises a base 10 and a bulb 11 having a pair of filaments 12, 13 sealed therein. The said filaments 12, 13 are in the form of helical coils having linear or straight-line axes, the filament 12 being preferably located in a plane passing through the longitudinal axis of the lamp with said filament disposed perpendicular to said axis, while the filament 13 extends transversely of said axis and at right angles to filament 12. In other words, the said filaments 12, 13 are arranged in substantially the shape of a T located in a plane extending transversely of, or perpendicular to, the lamp axis. Where standard bayonet pins 14, 15 are employed, they may be located on the base 10 in the same plane as the filament 12.

The filament 12 is secured at one end to a lead wire 15 and at its opposite end to a common lead wire 16. The filament 13 is secured at one end to the common lead wire 16 and at its opposite end to a lead wire 17. Portions of said leads 15, 16, 17 are sealed in the press portion 18 of a stem tube 19, the said leads extending to respective terminals or contacts in the base 10 so that

the filaments 12, 13 have separate circuit connections and may be independently energized.

The lamp is preferably mounted in the usual paraboloidal reflector of a headlamp so that the filament 12 extends through the focal point of the reflector in a vertical plane, and the filament 13 is in a horizontal plane. This filament arrangement in a headlamp employing a standard form of lens having vertical flutes across the middle and horizontal prisms at the top and bottom provides, with the vertical filament 12, a driving beam having a cross section in a vertical plane substantially as shown at 20 in Fig. 3. The said beam has a hot spot 21 of high intensity and relatively large depth at the middle of the beam, thereby providing a maximum of light straight down the roadway where it is most desirable. The horizontal filament 13 provides a beam having a cross-section in a vertical plane substantially as shown at 22 in Fig. 4 where the line H—H represents the horizontal plane. The said beam 22 has a very desirable wide lateral spread and affords a good meeting beam.

What I claim as new and desire to secure by Letters Patent of the United States is:

1. An electric incandescent lamp for vehicle headlamps comprising a bulb containing a pair of filaments with separate circuit connections, said filaments being straight linear filaments and being arranged substantially in the form of a T located in a plane perpendicular to the longitudinal axis of the lamp.

2. An electric incandescent lamp for vehicle headlamps comprising a bulb containing a pair of filaments with separate circuit connections, said filaments being straight linear filaments and being arranged substantially in the form of a T located in a plane perpendicular to the longitudinal axis of the lamp, the vertical leg of said T being located substantially in a plane extending through the said longitudinal axis of the lamp.

3. An electric incandescent lamp for vehicle headlamps comprising a bulb adapted to be mounted with its axis horizontal, a stem extending into said bulb axially thereof, three lead wires extending through said stem and projecting forwardly thereof one above the other, the middle lead wire having a laterally extending portion located directly above the end of the lower lead wire and a short end portion extending vertically upward and located on the opposite side of the bulb axis from the end of the upper lead wire, the ends of said lead wires and the laterally extending portion of said middle lead wire being

located in a plane perpendicular to the bulb axis, a filament connected at one end to the end of said lower lead wire and extending vertically upward and being connected at its other end to the said laterally extending portion of said middle wire, and a second horizontally disposed filament connected at each end to an end of said middle and upper lead wires and forming with said first-mentioned filament a T located in a plane 5 perpendicular to the bulb axis, and circuit connections for energizing said filaments separately.

4. An electric incandescent lamp for vehicle headlamps comprising a bulb adapted to be mounted with its axis horizontal, a stem extending into said bulb axially thereof, three lead wires extending through said stem and projecting forwardly thereof one above the other, the

middle and upper lead wires being offset one on each side of the bulb axis and each being bent toward the opposite side of said axis, the laterally extending portion of said middle lead wire being directly above the end of the lower lead wire, a filament connected at one end to the end of said lower lead wire and extending vertically upward and being connected at its other end to the said laterally extending portion of said middle lead wire, and a second horizontally disposed filament connected at each end to an end of said middle and upper lead wires and forming with said first-mentioned filament a T located in a plane perpendicular to the bulb axis, and circuit connections for energizing said filaments separately. 10 15

WILHELM HONING.
